UNITED STATES PATENT OFFICE.

OSCAR BOTO SCHELLBERG, OF NEW YORK, N. Y.

OPERATING TABLE.

Application filed March 18, 1922. Serial No. 544,871.

To all whom it may concern:

Be it known that I, OSCAR BOTO SCHELLBERG, a citizen of the United States, and a resident of the city of New York, borough of Manhattan, in the county and State of New York, have invented a new and improved Operating Table, of which the following is a full, clear, and exact description.

10 The present invention relates to new and useful improvements in operating tables, and it pertains more particularly to a table especially adapted for use in connection with the apparatus shown in my co-pending 15 application filed April 22, 1921, bearing Serial No. 463,702.

It is one of the primary objects of the present invention to provide a new and improved form of operating table especially 20 adapted for use in operations for treating the alimentary canal.

It is a further object of the invention to construct the operating table so that the patient may occupy a horizontal position, 25 a sitting position, or a position between the two.

It is a further object of the invention to provide means in connection with the table for supporting a three-way valve, the 30 construction of which forms a portion of the subject-matter of the above-mentioned application.

It is a further object of the invention to provide a table in which the adjustable foot rest is employed.

35 It is a further object of the invention to construct the table so that it may be connected with a suitable sewer system.

With the above and other objects in view, 40 reference is had to the accompanying drawings, in which—

Figure 1 is a view in side elevation of a table constructed in accordance with the present invention;

45 Fig. 2 is a detail sectional view showing the adjustable foot rest construction;

Fig. 3 is a detail sectional view taken on the line 3—3 of Fig. 2;

Fig. 4 is a top plan view of the operating table;

Fig. 5 is a transverse sectional view taken on the line 5—5 of Fig. 4;

Fig. 6 is a vertical sectional view of the operating table and stand;

55 Fig. 7 is a horizontal sectional view taken on the line 7—7 of Fig. 6.

Referring more particularly to the drawings, the reference character 10 designates a base and rigidly carried thereby and projecting vertically therefrom is a hollow standard 11. The upper end of the hollow standard 11 is provided with an enlarged flange 12, and rigidly carried by said enlarged flange 12 is a rigid seat portion 13. This tubular standard 11 is provided with a sight opening 14, and mounted within the hollow standard in a position behind the sight opening 14 is a transparent hopper 15. This hopper 15 has a contracted lower end 16, which is received within a fitting 17, said fitting 17 being supported within the hollow standard 11 by means of a spider or the like 18. Having screw-threaded engagement with the fitting 17, as at 19, is a length of pipe 20, 75 and connected to said pipe 20 is an elbow 21, to which is connected a length of pipe 22, this last-mentioned length of pipe 22 extending through an opening 23 in the hollow standard 11. This length of pipe 20 is connected as at 25 to an elbow 24, which forms the means by which it is connected to a suitable sewer line 26, more clearly shown in Fig. 1. The hopper 15 is graduated as at 15', the purpose of which 85 will be hereinafter more specifically described.

Interposed between the upper end of the hopper 15 and the seat section 13, is a rubber gasket 27 by means of which a tight 90 joint between the upper edge of the hopper 15 and the side sections 13 is maintained.

Located within the hollow standard 11, at a point diametrically opposite the sight opening 14, is an electric element 30, said electric element 30 receiving its power from the line 31 and serving to illuminate the hopper 15 in order that the contents thereof may be examined through the sight opening 100 14. Mounted in the fitting 17 heretofore mentioned is a valve 33, and said valve 33 is controlled by means of a lever 34 operating in an opening 35 formed in the hollow standard 11. By this means the valve may 105 be opened at will to discharge the contents of the hopper into the length of pipe 20.

Leading into the hopper is a pipe 36 connected to a supply line 37, and said pipe 36 has its inner end positioned within the hopper and curved as indicated by the reference character 38. By this means the hopper is 110

flushed and cleaned at will by operation of the valves 40 shown in Fig. 1, said valves controlling the flow of fluid from the main line 41 to the line 37 and hence to the hopper 15 per 15.

Pivots secured as at 50 to the rigid seat section 13 is a foot section 51 and said foot section 51 comprises side rails 52, the top of the table being formed from glass or other suitable transparent material 53. The reference character 54 designates a vertically standing foot rest and said foot rest carries a rearwardly projecting rack member 55 which is secured to the foot rest at a point substantially centrally of the ends thereof.

Extending transversely of the foot section 51 and mounted in the side rails 52 is a shaft 56, and secured to said shaft in a position 20 where it will engage the rack 55 is a pinion 57. This shaft 56 is provided with a hand wheel 58 by means of which it is rotated to move the foot rest 54 towards or away from the foot section 51 at the will of the operator.

Extending vertically from the rigid seat section 13 is a bracket 60 and pivotally mounted on the upper end of said bracket is an arm 61. Pivots secured as at 62 to 30 said arm 61, is an arm 63, and pivotally secured to the arm 63 as at 64, is an arm 65. As more clearly shown in Fig. 4, the arm 66 is pivotally secured as at 67 to the arm 65, and rigidly secured to the outer free end 35 of the arm 66 are two curved arms 68. These curved arms are each provided with a grooved lug 69, and said grooved lug and curved arm 68 are so shaped as to receive and provide a support for a three-way valve 40 70. Connected to one outlet of the three-way valve 70 is a tube 71, by means of which the treatments are carried out, and leading from another of the outlets of the three-way valve 70 is a tube 72 leading to a jar 45 or other suitable receptacle 73. Leading to the three-way valve 70 is a tube 74, and said tube 74 is connected to a Y-fitting 75, the branches of which lead to receptacles 76 and 77 carried by a suitable bracket 78. This 50 last-mentioned structure forms the subject-matter of my copending application above mentioned and is merely mentioned here for the purpose of describing its relation to the apparatus disclosed herein.

Pivots secured as at 80 to the rigid seat section 13, is a back section 81, and as more clearly shown in Fig. 5, this back section comprises angular side rails 82 in which a cushion 83 is removably secured by a plurality of spring clips or the like 84. Each of these angular side rails is provided with a curved slotted member 85, and operating in said curved slotted members 85 is a bolt 86 enclosed in a suitable sleeve 87. One end 65 of this bolt 86 is threaded as at 88, and en-

gaged therewith is an operating handle 89 by means of which suitable friction may be had to cause a binding or gripping of the curved members 85 between the flanged ends 90 of the sleeve 87 and nuts 91 carried by the 70 rod 82 to secure the table in adjusted position.

Projecting from the foot section 51 on opposite sides thereof are, brackets 100, and pivotally connected as at 101 to each of said 75 brackets is an outwardly extending lever 102, the rear end of which is pivotally connected as at 103 to an angular lever 104, which in turn is pivotally mounted on the rod 86 as more clearly shown in Fig. 5. Each 80 of these levers 102 is provided with an arm rest 107 and said levers 102 are adapted to form the arms of the table when the same is adjusted to retain the patient in a sitting position, as shown by dotted lines in Fig. 1. 85

By this construction it is apparent that the connecting levers 102 in addition to forming the arms of the table serve to cause an operation in unison of the foot section and the back section of the table. Furthermore, it will be noted that when the table is adjusted with the foot section and the back section in the same horizontal plane as the seat section, the levers 102 forming the arms of the table will fold down into 95 parallelism with the sides of the rigid seat section 13 and will thus be out of the way when the table is in its adjusted position.

The device functions in the following 100 manner:

The first part of the operation for which the table is adapted for use is carried out with the patient in a horizontal or lying position. With the table adjusted as shown 105 in full lines in Fig. 1, the patient will occupy a horizontal position, and owing to the relative position of the brackets which support the three-way valve 70, the three-way valve is capable of movement toward 110 the patient in order that the tube 71 may be properly manipulated. After the first part of the operation is carried out, the table is moved to the dotted-line position shown in Fig. 1, thus bringing the patient to 115 a sitting position for the remainder of the operation. The result of the operation is collected in the hopper 15, the graduations 15' thereon serving to measure the volume of material and liquid discharged. This 120 discharge may be disposed of through the sewer system 22 or the same may be retained within the hopper 15 for analysis or other purpose.

From the foregoing it is apparent that 125 the present invention provides a new and improved form of operating table especially adapted for carrying out operations upon the alimentary tract, and, at the same time, provides means for collecting and retaining 130

the result of the operation for inspection and analysis. Furthermore, the invention provides an operating table in which the entire operation may be carried out without

opening for operating said valve, and a seat section carried by the upper end of said pedestal and having an opening disposed above the measuring receptacle. 25

5 necessitating the removal of the patient, and, at the same time, with the maximum amount of comfort on the part of the patient, as well as an easy manipulation of the apparatus employed.

2. An operating table comprising a hollow pedestal provided with a sight opening and a slot therebeneath, a drain extending partially through said pedestal, said drain having its upper end terminating at a point 30

10 What I claim is:

substantially opposite the bottom of said

15 sight opening, means in said pedestal for comprising a hollow pedestal provided with a sight opening and a slot disposed therebeneath, a spider formed interiorly of said pedestal, a drain supported by said spider and extending through the pedestal a measuring receptacle supported by said drain at a point opposite said sight opening, a valve for controlling the discharge

35 beneath the sight opening, and a receptacle supported on the open upper end of said drain, said receptacle having graduations positioned opposite the sight opening in the pedestal.

20 from said measuring receptacle, a lever extending through the slot beneath the sight

OSCAR BOTO SCHELLBERG.
